[57] CLAIM

The ornamental design for a solar powered light, as shown and described.

DESCRIPTION

FIG. 1 is a top plan view of a solar powered light showing my new design thereof;

FIG. 2 is an elevational view of the claimed design;

FIG. 3 is a bottom plan view of the claimed design;

FIG. 4 is an elevational view of the claimed design rotated 90 degrees from the view shown in FIG. 2;

FIG. 5 is a perspective view of the claimed design;

FIG. 6 is a perspective view of a second embodiment of the solar powered light fixture, it being understood that the second embodiment differs from the first embodiment only by the omission of the slots in the sides of the top solar cell housing; and,

FIG. 7 is a perspective view of a second embodiment of the solar powered light fixture, it being understood that the second embodiment differs from the first embodiment only by the omission of the slots in the sides of the top solar cell housing and by the smooth surface of the cylindrical diffuser.
